WELL TREATING APPARATUS

Leonard C. Chamberlain, Midland, Mich., assignor to The Dow Chemical Company, Midland, Mich., a corporation of Michigan

Application February 25, 1942, Serial No. 432,184

3 Claims. (Cl. 166—10)

The invention relates to a device useful for facilitating the positioning of various tools in a well bore, such as whipstocks, packers, and the like. It more particularly concerns a device adapted to be connected to the lower end of a packer or the like, said device being longitudinally adjustable while maintaining engagement with the bottom of the well bore so as to allow the packer or other tool to assume the desired position, after which the anchoring device may be locked in such a manner as to support the weight of the tool and a portion of the run-in string thereabove.

It is sometimes desirable in treatments employing tools such as a packer of the type commonly referred to as an "anchor packer" which is seated or expanded by allowing the weight of the run-in string to rest on the top of the packer while the packer is supported about its lower end, to be able to select the position at which the packer is to be seated after it has been lowered in the well bore or to vary the location of the seal produced by the packer as the treatment progresses.

It is, therefore, the principal object of the invention to provide a device adapted to be attached to the lower end of a well tool, which is capable of longitudinal adjustment in a manner to support the tool at any desired position and any additional weight due to pressure being applied on top of the tool.

Another object of the invention is to provide a longitudinally adjustable locking anchor for well tools such as packers, whipstocks, and the like.

Another object is to provide a device which is especially suitable for seating an anchor-type packer at various locations as desired.

Still other objects and advantages of the invention will be apparent from the following description and accompanying drawings wherein:

Fig. 1 is a view in sectional elevation showing the device in the lower portion of a well bore associated with an anchor packer in such a manner as to permit seating the packer by means of the new device.

Fig. 2 is a sectional elevational view of the same apparatus shown in Fig. 1 with the packer raised and seated at the desired location and the parts of the device assuming a different relation.

Fig. 3 is a sectional elevational view similar to that of Fig. 1 showing a slightly modified form of the apparatus.

Fig. 4 is a view similar to that of Fig. 1 showing still another modification of the anchoring device.

Fig. 5 is another view in sectional elevation of

the apparatus of Fig. 4 wherein the various parts of the apparatus have assumed a different relationship.

As shown in Fig. 1 the lower portion 1 of the well bore has traversed an impervious stratum 2 and ended in a stratum 3 of a productive nature at point 4. The apparatus is shown positioned in the well bore by means of the tubing string 5 which is connected to the packer 6 by means of collar 7. The packer comprises upper and lower 5 head members 8 and 9 respectively, which are suitably formed to support and retain the packer rubber 10. A mandrel 11 forms a passageway through the packer and is rigidly attached to the upper packer head 8 while being adapted to 10 slide in lower head member 9. The lower end of the mandrel 11 is provided with an outwardly projecting flange 12 which serves to limit upward travel of the mandrel 11 as it abuts the shoulder of the lower packer head 9, thus serving 15 to hold the two packer heads and the packer rubber together and in proper relation. Attached to the lower packer head 9 is swage coupling member 13 which allows the mandrel 11 to extend below the packer head member as it slides 20 through the packer head 9. Swage member 13 is attached by means of conventional coupling member or collar 14 to a perforate section of pipe 15 through which fluid may be ejected into the well bore from the tubing 5 or withdrawn from 25 the well bore and conducted to the surface. The perforate pipe 15 is connected to a tubular element 17 by means of a second coupling or collar 16. The lower end of the tubular element 17 is provided with an outstanding flange portion 18 which is adapted to abut shoulder 19 on body member 20. A collar member 21 is threadedly 30 connected to body member 20 and slidably mounted on the tubular member 17. Shear pins 22 detachably connect the collar member 21 to 35 the tubular member 17. Body member 20 depending from the collar 21 is formed in such a manner as to provide a downwardly tapered annular chamber 23 between the tubular member 17 and body member 20. Steel or other suitable 40 balls 24 are adapted to drop in the tapered chamber 23 and engage the tubular element 17 and the body member 20 in wedging relation so as to prevent downward movement of tubular element 17 relative to the body member 20. An annular 45 groove 25 is provided in the tubular element 17 at a point adjacent the balls 24 so located that when shear pins 22 are holding the collar 21 on tubular element 17 it is ready to receive the balls 50 24 as they topple into groove 25 upon downward 55 movement.

movement of element 17 relative to body member 20. A tubular element 26 closed about its lower end engages body member 20 and completely surrounds the lower end of tubular element 17.

In Fig. 2 the pins 22 have been sheared permitting the tubular element 17 and packer 6 to be raised to the desired point for seating, after which allowing the weight of the tubing to rest on the packer has wedged the balls 24 against body member 20 and tubular element 17 and caused the mandrel of the packer to move downwardly thus expanding the rubber against the impervious stratum 2.

In the modification shown in Fig. 3 the tubular element 17 has been replaced by a somewhat similar tubular member 27 having an outstanding flange 18 about its lower end. Tubular member 27 differs from similar element 17 in that it is provided with a section 28 of smaller diameter which is located at a point adjacent the downwardly tapered chamber 23 formed in body member 20—a when the shear pins 22 hold the collar 21 in engagement with member 27. The reduced diameter, section 28 prevents slips 29 from engaging the tubular element 27 while the slips rest on shoulder 30 of member 20—a. After pins 22 have been sheared and the tubular member 27 raised to a point where the element 27 assumes a greater diameter the slips are adapted to engage the tubular member 27 to prevent downward movement thereof relative to body member 20—a.

In the modification shown in Fig. 4 the perforate pipe 15 is connected by collar 16 to tubular element 31 which is provided with an outstanding flange 32 at its lower end. The flange 32 serves to engage the lower end of sleeve 33 surrounding member 31 and move it upwardly while a lug portion 34 adjacent the upper end of tubular element 31 is adapted to engage the upper end of the sleeve 33 and move it downwardly depending upon the relative movement of tubular element 31. The sleeve 33 is provided with a packing gland 35 at its lower end which is adapted to hold the sleeve 33 at any position in lower tubular element 26 unless the flange 32 or lug 34 engage and move the sleeve. In this modification the body member 36 is so formed when the sleeve member is adjacent the body member balls 24 are pushed out of tapered chamber 23 and rest on shoulder 37 formed in the body member. The upper end of body member 36 is threadedly connected to collar member 38 so formed as to clear the lug portion 34 of member 31 as the lug is lowered into the body member.

In the view shown in Fig. 5 the sleeve 33 has been engaged by upper lug 34 and moved out of tapered chamber 23 allowing balls 24 to fall into tapered recess 23 to provide the necessary wedging action when tubular element 31 is lowered relative to the body member 36. In general the tubing will be lifted or raised and thus the lug 34 will be moved out of the tapered chamber 23 before the balls are wedged in place and the packer seated.

In the operation of the modification shown in Fig. 1 the apparatus assembled as shown is lowered to the bottom of the well bore by means of the tubing 5. The tubular element 26 is positioned to engage the bottom of the well bore at a point 4 and as additional weight is allowed to rest on the element 26, consisting of the tubing string 5 or a portion of it, the pins 22 are caused to shear while the balls 24 topple into

the annular groove 25 as the tubular element 17 moves downwardly. Thereafter the tubing string 5 may be picked up or raised in the well bore until the packer 6 is located adjacent the desired stratum such as, for example, impervious stratum 2. Thereafter the tubing 5 is again lowered which operation causes the balls 24 to wedge in the tapered chamber 23 thus providing support for the lower end of packer 6. As additional weight is applied to the top of the packer by means of the tubing 5 the packer rubber is compressed as shown more clearly in Fig. 2 and caused to expand against the well bore walls effecting a seal therewith. Thereafter fluid may be introduced into the tubing 5 and ejected therefrom into the producing stratum 3 if desired or fluid may be withdrawn from stratum 3 and conducted to the surface. The tool is thus especially suitable for acidizing operations or the placement of cement at the desired location. In addition, by changing the location of the perforate pipe 15 to a point above the packing element 6 the device may be used to seal off production from the lower portion of the formation while producing or introducing fluid at a point above the packing element.

In the modification shown in Fig. 3 slips 29 have been substituted for the balls 24 of Figs. 1 and 2, but the operation is substantially identical with that of the apparatus shown in Fig. 1. In operation of the device of Fig. 3 the shear pins 22 are sheared as weight is allowed to rest on the packer 6 and the tubular element 26 while the slips 29 are held out of engagement with the section 28 of tubular element 27 on shoulder 30 of body member 20—a. After the pins have been sheared, raising the tubing 5 lifts the packer 6 and the tubular element 27 upwardly and after the desired location is reached allowing the weight of the tubing and the packer to rest on the tubular element 27 causes the slips 29 to engage the thicker walls of element 27. Thus the lower end of the packer 6 is supported and, as additional weight is brought to rest on the top of the packer, the packer rubber 10 is caused to distend and effect a seal with the bore wall adjacent stratum 2. It will be evident that the shear pins 22 will be chosen of such strength as to support the tool without causing the packer to seat as the necessary weight is applied to cause shearing of the pins.

In the modifications shown in Figs. 1 and 3, once the shear pins have been broken and the packer seated, it is still possible to seat the packer at points higher up in the well bore, but it is never possible to return to the bottom of the well bore and seat the packer at a lower location without first withdrawing the tool from the well bore and replacing the shear pins.

In the modification shown in Fig. 4 there is provided means whereby the packer may be seated at various locations upwardly in the well and thereafter the packer may be returned to its lowermost position and reseated throughout the range of the anchoring tool without withdrawing the tool from the well bore. This operation is made possible by the fact that the sleeve 33 can be positioned so as to displace the wedging balls 24 from the tapered chamber 23 when the tubing is raised to a point where lugs or flange 32 push the sleeve upward. Thereafter as the tubular element 26 is allowed to engage the bottom of the well bore lowering the tubing 5 and packer 6 allows the tubular element 31 to move downwardly to the fullest extent of its downward travel. During the latter part of such movement lug 34

will have engaged the sleeve 33 and moved it down so that balls 24 can fall into tapered chamber 23. Thereafter the balls 24 are then ready to lock tubular element 31 relative to tubular element 26 at any point of their telescoping travel. For example lifting on the tubing 5 then lifts the tubular element 31 while the sleeve 33 is retained at the lower end of the tubular element 29 due to the frictional action of the packing gland 35 holding against the walls of the tubular element 26. Thereafter the balls 24 will wedge and support the lower end of the packer as the weight of the tubing string is caused to rest on the top of the packer. Thus if at any time it is desired to seat the packer at a lower location in the well bore, it is only necessary to raise the tubing string to a point where the lugs 32 on tubular element 31 pick up the sleeve 33 and moves it upwardly to displace the balls 24 from the tapered chamber 23. When the sleeve has accomplished this result the tool may be again lowered to its lowest position and seated at any point within the range of the apparatus.

It will be evident that more than one of any of the anchoring devices shown may be used in combination, in which case the second anchoring device might be adapted to telescope over and cooperate with member 26, the latter element being modified to serve the purpose of tubular elements 17, 21, and 31 of the various modifications. In such a structure it would be necessary to add an additional tubular member to serve the present purpose of member 26. By such an arrangement the device could be made to have the shortest possible length in a collapsed form and the greatest possible length in the extended form.

In the foregoing manner packers of the anchor type and many other tools can be positioned at various locations in the well bore as desired after they have been lowered into the well bore or as the results of a treatment indicate that the position may be desirably varied.

I claim:

1. In a longitudinally adjustable anchor device for use in well bores the combination which includes upper and lower rigid tubular members in telescoping engagement, shearable means holding the lower member against telescopic movement relative to the upper member, locking means associated with the telescoping members adapted to lock the upper tubular member against downward movement relative to the upper tubular member after the shearable means has been sheared.
2. In a longitudinally adjustable anchor device for use in wells the combination which includes upper and lower tubular members in telescoping engagement, means to lock the upper tubular member against downward movement relative to the lower tubular member while permitting the upper tubular member to move upwardly, and means for disengaging said locking means when said tubular members are in extended telescopic relationship.
3. In a longitudinally adjustable anchor device for use in well bores the combination which includes an upper tubular member and a lower tubular member, said members being in telescoping engagement, a body member attached to the outer of said tubular members, a shear pin holding the body member to the inner telescoping member, and latching means carried within said body member adapted to allow the upper telescoping member to be moved downwardly relative to the lower telescoping member to permit shearing of the shear pin and to thereafter lock upon downward movement of the upper telescoping member relative to the lower telescoping member while permitting the upper telescoping member to move upwardly relative to the lower telescoping member.

40

LEONARD C. CHAMBERLAIN.
